APPARATUS FOR BENDING WIRE

Arnold L. Patterson, Harmony, N.C., assignor to Western Electric Company, Incorporated, New York, N.Y., a corporation of New York

Filed Sept. 8, 1965, Ser. No. 485,803
8 Claims. (Cl. 140—102)

ABSTRACT OF THE DISCLOSURE

A wire lead advanced between an anvil pin and a stationary stop engages a conductive stop and completes an electrical circuit from the conductive stop through the pin to energize a mechanism to rotate a bending element about the anvil pin. As the bending element is rotated, the lead is bent about the anvil pin whereafter the anvil pin is retracted from engagement with the wire lead. The bending element is further rotated to press the end of the wire lead against that portion of the lead between the bent end and the stationary stop.

This invention relates to apparatus for bending wire and more particularly to apparatus for bending a section of the wire flat against the unbent section.

In the assembly of coaxial connectors, machines for bending the leads of components are employed. It is necessary to bend the ends of stripped insulated leads back upon themselves to permit subsequent insertion of the bent ends into coaxial connectors. One requirement for these bent leads is that they do not include a bight or loop; that is, the bent section must be flat against the unbent section.

An object of this invention is to provide new and improved apparatus for bending a wire against itself.

Another object of this invention is to provide apparatus for bending a wire flat against itself with no bight or loop.

It is a further object of this invention to provide an apparatus for bending a wire utilizing the presence of the wire to complete an electrical current to initiate the operation of the apparatus.

With these and other objects in view, the present invention contemplates a bending apparatus having a bending projection which circumferentially bends a wire about an anvil pin for approximately 90° and then bends the wire against itself after the anvil pin is removed. Facilities are provided to initiate operation of the apparatus upon loading the wire in the proper position with respect to the anvil pin. The anvil pin is removed after approximately 90° movement of the bending projection by a cam surface located on a cylinder upon which the bending projection is mounted. This cam surface co-operates with a cam follower connected to the anvil pin so that the pin is fully withdrawn from the wire as the bending projection acts to bend the wire upon itself.

These and other objects, aspects, and advantages of this invention may be appreciated from the following detail description and from the accompanying drawings, in which:

FIG. 1 is a plan view of a wire bending apparatus embodying the principles of the invention;

FIG. 2 is a partial cross-sectional view taken along line 2—2 of the apparatus shown in FIG. 1 illustrating a drive mechanism for operating facilities to bend a wire upon itself;

FIG. 3 is a partial cross-sectional view taken along line 3—3 of FIG. 2 showing a wire positioned between a bending member and a conductive stop to initiate operation of the apparatus;

FIG. 4 is a cross-sectional view taken on line 4—4 of

2

FIG. 2 illustrating the construction of a support post within the frame of the bending apparatus;

FIG. 5 is an isometric view illustrating camming facilities for removing a first bending member to allow a second bending member to bend the wire upon itself;

FIGS. 6, 7 and 8 depict the operation of the bending elements during a cycle of operation of the bending apparatus to bend a section of wire upon itself without forming a bight; and

FIG. 9 is an electrical circuit schematic for initiating and controlling the operation of the bending apparatus.

Referring generally to FIGS. 1 and 2, a bending apparatus is shown for folding a stripped end 13 of an insulated wire 14 back upon itself. The bending is accomplished by positioning the stripped end 13 of insulated wire 14 between a bending member or projection 16 and another bending member or anvil pin 17. The bending projection 16 extends from the top of a cylinder 18 (see FIGS. 2 and 5) mounted for rotation in an aperture formed in a housing 12 secured to a base 11. The cylinder 18 is provided with a bore 19 and a counterbore 20 to slidably accommodate a post 21 upon which the anvil pin 17 is mounted. The post 21 has a bottom portion 22 which is of a rectangular configuration and sits within a slot 23 formed in the housing 12 (see FIGS. 3 and 4). The rectangular bottom portion 22 of the post 21 precludes rotation of the post 21 while permitting axial movement of the post within the counterbore 20 of the cylinder 18. A spring 24 (see FIGS. 2 and 3) acts against the rectangular bottom portion 22 of the post 21 to maintain the anvil pin 17 extending through the bore 19 and laterally aligned with the bending projection 16.

Mounted on the cylinder 18 is a pinion 26 that engages a rack 27 (see FIGS. 1 and 2). One end of this rack 27 abuts a return spring 28 and the other end is connected through a spring coupling 29 to a piston rod 31 mounted in a fluid cylinder 32. The return spring 28 is selected to be considerably weaker than the spring contained in the spring coupling 29. When the cylinder receives fluid, the piston rod 31 and the rack 27 are advanced to rotate the pinion 26 and, hence, the cylinder 18. Rotation of the cylinder 18 moves the bending projection 16 against the stripped end 13 of the wire 14 to bend the wire about the anvil pin 17 (see FIG. 7).

The bottom of cylinder 18 is machined to provide a cam surface 33 (see FIG. 5) that acts against a cam follower or follower pin 34 radially extending from the base of the post 21. Inasmuch as the post 21 is mounted for sliding movement relative to cylinder, the cam 33 is effective, upon rotation, to present a lobed or high portion to move the follower pin 34 and thus the post moves down against the spring 24 to withdraw the anvil pin 17. Continued movement of the bending projection 16 now forces the stripped end 13 of the wire 14 against a stationary conductive stop 36 (see FIGS. 1 and 8) whereupon the bight or loop formed in the wire 14 during the initial bending operation (see FIG. 7) is collapsed and the wire is doubled against itself.

Considering now the initiation of operation of the apparatus and referring to FIGS. 3 and 9, an attendant inserts the stripped end 13 of the wire 14 into the bending apparatus 11 to complete an electrical circuit between a conductive stop 37 and the anvil pin 17 or other contacted members such as the stop 36 or the bending projection 16. The conductive stop 37 is mounted in a notch formed between an insulator strip 44 and an insulator holder plate 45. The circuit completed through the anvil pin and the conductive stop 37 energizes a relay coil 38 from a power supply 39. Energization of relay coil 38 closes contacts 40 to complete a locking circuit from the power supply 39, through a normally closed limit switch

35, the locking contacts 40 and the relay coil 38. The energization of relay coil 38 also closes relay contacts 41 to complete a circuit from the power supply 39 to energize a solenoid 42 that controls a valve (not shown) to admit fluid to the fluid cylinder 32.

When fluid is admitted to the cylinder 32, the piston rod 31 is advanced to move the rack 27 against the pinion 26. The pinion 26, in turn, rotates the cylinder 18 and the bending projection 16. The bending projection 16 bends the stripped end 13 of the wire 14 about the anvil pin 17 (see FIG. 7). After the stripped end 13 of the wire 14 is bent approximately 90° about the anvil pin 17, the cam surface 33 of the cylinder 18 acts against the follower pin 34 to longitudinally force the pin 21 to move down against the spring 24 to remove the anvil pin 17 from the wire 14.

The locking circuit through normally closed limit switch 35, the contacts 40, and the relay coil 38 maintains operation of the fluid cylinder 32 after the stripped end 13 of the insulated wire 14 is bent and removed from the engagement with the conductive stop 37. Further, rotation of bending projection 19 bends the stripped end 13 of the wire 14 against the stationary stop 36 whereupon the bight or loop formed in the wire 14 during the initial bending operation is collapsed and the wire is doubled against itself (see FIG. 8).

After the completion of the bending cycle, the relatively weak return spring 28 is compressed to act as a stop for the rack 27; however, the piston 31 continues to advance to compress the relatively strong spring in spring coupling 29 (see FIG. 1). A cam 43 on the advancing spring coupling 29 opens normally closed limit switch 35 to de-energize relay coil 38. The de-energization of the relay coil 38 opens the contact 41 to de-energize the solenoid 42 to operate the valve (not shown) to interrupt the flow of fluid to the cylinder 32 and connect the cylinder to a fluid exhaust line. The compressed return spring 28 and compressed spring coupling 29 then restores the rack 27 and piston 31 to the original position. The return movement of the spring coupling 29 removes cam 43 from the limit switch 35 to permit the switch 35 to again close. The apparatus is now in condition to execute another cycle of operation upon the attendant positioning the stripped end 13 of another insulated wire 14 between the anvil pin 17 and the conductive stop 37.

It is to be understood that the above-described apparatus and construction of elemental parts are simply illustrative of an application of the principles of the invention and many other modifications may be made without departing from the invention.

What is claimed is:

1. An apparatus for bending an article, a first bending element, a second bending element spaced from the first bending element, normally unoperated means including a deenergized electrical circuit for imparting relative movement between said bending elements to bend an article positioned therebetween, a conductive stop; and means responsive to the positioning of an article between both of said bending elements and in engagement with one of said bending elements and said conductor stop for energizing said circuit and initiating operation of said normally unoperated means.
2. An apparatus for bending wire comprising, a first bending element mounted for axial movement, a second bending element spaced from and rotatably mounted for circumferential movement about the first bending element, normally unoperated means for rotating the second bending element, means responsive to the positioning of a wire between both of said bending elements and in engagement with one of said bending elements for initiating opera-

tion of said normally unoperated means to rotate the second bending element,

5 a stop for engaging the wire while the second bending element circumferentially moves about the first bending element to bend the wire, and

means rendered effective by a predetermined movement of the second bending element to axially move the first bending element out of engagement with the wire whereupon the second bending member bends the wire against the stop.

3. In an apparatus for bending a wire utilizing the presence of the wire to be bent to start the bending operation comprising,

an anvil pin,

10 a post upon which the anvil pin is mounted having a cam follower radially mounted near the base of the post,

a rotatably mounted cylinder concentric with and surrounding said post having a cam surface cooperating with the cam follower to move the post and anvil pin within the cylinder after a predetermined rotation of the cam surface,

15 a bending projection radially extending from and mounted on the top of the cylinder for circumferential movement about the anvil pin,

a conductive stop for engaging the wire while the bending projection moves about the anvil pin, a spring longitudinally biasing the post to position the anvil pin slightly above the bending projection,

20 a power supply,

a relay coil connected in series with the power supply, a second conductive stop,

25 a circuit including said conductive stop, said anvil pin, said power supply, said relay coil and the wire to be bent,

a solenoid,

30 a pair of normally open circuit contact means responsive to the energization of said relay coil for completing a series electrical circuit with the power supply and the solenoid valve, and

35 means responsive to the energization of said solenoid for rotating the cylinder for bending the wire about the anvil pin and for moving the cam surface of the cylinder against the cam follower to force the post against the spring to remove the anvil pin after said predetermined rotation whereafter further rotation of the bending projection doubles the wire against itself.

4. In an apparatus for bending the end of an electrically conductive wire,

40 a first conductive bending element, a second conductive bending element spaced from said first bending element for cooperating with said first bending element to bend a wire positioned therebetween,

45 a conductive stop spaced from said bending elements and engaged by the wire positioned between said bending elements,

50 normally unoperated means including a first spring for imparting through said spring relative motion to said first and second bending elements to bend said wire,

55 a relay circuit for operating said relative motion imparting means,

60 an energizing circuit completed by said engagement of said wire with said conductive stop and either of one of said bending elements for energizing said relay circuit,

65 a second spring weaker than said first spring for initially opposing and subsequently limiting relative movement of said bending elements whereupon said first spring is subsequently compressed, and

70 means rendered effective upon compression of said spring for interrupting and de-energizing said relay circuit.

5. In an apparatus as defined in claim 4 wherein the means for imparting relative movement to said bending elements advances the wire from engagement with the conductive stop, and

a locking circuit operated by the energization of said relay circuit for maintaining said relay circuit energized after said wire advances from engagement with said conductive stop.

6. An apparatus for bending wire comprising, a first bending element mounted for axial movement, a second bending element spaced from and mounted for circumferential movement about the first bending element to engage a wire positioned therebetween, means rendered effective by a predetermined movement of the second bending element for axially moving the first bending element from engagement with the wire,

a stop for engaging the wire while the second bending element circumferentially moves about the first bending element, and

means for rotating the second bending element to bend the wire about the first bending element and then axially move the first bending member whereupon the second bending member bends the wire against the stop.

7. An apparatus for doubling a wire on itself comprising,

an anvil pin against which said wire is placed, a post upon which the anvil pin is mounted having a cam follower radially mounted near the base of the post,

a rotatably mounted cylinder concentric with and surrounding said post having a cam surface cooperating with the cam follower for axially moving said post after 90° rotation of said cylinder,

a bending projection mounted on the top of the cylinder and offset with respect to the axis of said cylinder, a stop for engaging the wire while the bending projection circumferentially moves about the anvil pin,

a spring longitudinally biasing the post and anvil pin in lateral alignment with the bending projection, and

means for rotating the cylinder to bend the wire against the anvil pin and to then move the cam surface against the cam follower to force the post against the spring to remove the anvil pin while continued rotation of the bending projection doubles the wire against itself.

8. An apparatus for doubling a wire against itself comprising,

a hollow cylinder having a cam surface near the base of said cylinder,

a post concentrically positioned with said hollow cylinder having a radially mounted follower pin located near the base of said post for cooperation with the cam surface of said cylinder to axially move said post after 90° rotation of said cylinder,

an anvil pin axially mounted on top of said post and against which said wire is placed,

a bending projection mounted on the top of said cylinder for circumferential movement with the cylinder about said anvil pin,

a stop for engaging the wire while the bending projection circumferentially moves about the anvil pin,

a spring longitudinally biasing the post and the anvil pin to position said anvil pin in lateral alignment with the bending projection, and

means for rotating the cylinder to bend the wire about the anvil pin, and for moving the cam surface of the cylinder against the follower pin to force the post against the spring to remove the anvil pin from engagement with the wire while continued rotation of the bending projection doubles the wire against itself.
